SAMUEL MARCUS, OF BROOKLYN, NEW YORK, ASSIGNOR TO MARKON MANUFACTURING CO., INC., OF NEW YORK, N. Y., A CORPORATION OF NEW YORK

MOUNTING FOR DOLL-EYE SETS

Application filed March 6, 1926. Serial No. 92,728.

This invention relates to mountings for eye sets for dolls, display figures and the like, such that the eyes may be positioned properly at the eye-sockets. One of the objects of the invention is to provide suitable and reliable means for firmly anchoring the eye set in position in the head of a doll or the like, in a simple, convenient and practical manner. Still other objects are to generally improve the construction of eye sets, and to provide a decided advance in the art to which the invention relates.

These being among the objects of the present invention, the same consists of certain features of construction and combinations of parts to be hereinafter described and then claimed with reference to the accompanying drawings illustrating a preferred embodiment of the invention, in which

Fig. 1 is a vertical central section, on the line 1—1 Fig. 2, of the face portion of a doll, showing the improvements applied thereto;

Fig. 2 is a rear elevation of the improved mounting for a doll eye set showing the set in place in a head, which is shown in section;

Fig. 3 is a section on the line 3—3 Fig. 2, of the improved means for anchoring a doll eye set in position in the head;

Fig. 4 is an elevation of the formed portion of the head at the place where the anchoring is established; and

Fig. 5 is a sectional detail similar to Fig. 3 but illustrating a slight modification.

Referring to Figs. 1 and 2, the face portion 10 of the head of a doll or the like may be composed of any suitable material, having eye sockets at which the right eye 11 and the left eye 12 slightly protrude, more or less in imitation of natural eyes. Each eye 11, 12 is preferably provided with a hemispherical metallic foundation shell 13, an outer thin transparent shell 14, and an intermediate thin opaque shell 15 on which the iris is printed. The thin shells are preferably composed of celluloid. The shells 14 and 15 are preferably drawn over the foundation shell 13 and the eye structure assembled and made in the usual or any other suitable manner.

The eyes 11, 12 are mounted on and connected together by means of a bridge rod 17,

so as to provide a pair of united eyes. In order to mount each eye on the bridge rod 17 so that the eyes may roll and be brought to open eye position or sleeping eye position, each eye 11, 12 is provided with a back member 18 having at opposite sides but within the eye structure, perforated lugs 19 as indicated in dotted lines Fig. 2. The back members 18 of the respective eyes 11, 12 are provided with slots 22, 23, each slot extending in a plane 55 substantially at right angles to the bridge rod. The eyes are provided with an actuating weight 25 preferably having a cushion-buffer 28 of cork or any other suitable material for the purpose of eliminating noise when 60 striking the inside of the chin of the doll or other head.

A suitable piece of wire is bent into suitable shape as illustrated in Fig. 2, to provide arms 29 and 30, which are joined by a 70 loop 31. This loop is inserted between weight sections 24, 26, and a pin 27 passes through the loop whereby to secure the weight to the arms 29, 30. The arms 29, 30 are furthermore bent so as to provide open humps 32, 33 adjacent their extremities, said open humps being opposite each other; that is to say, the gaps or openings in the humps are in alignment.

The assembly or organization of the artificial eyes 11, 12 with the arms 29, 30 is accomplished by first passing the humps 32, 33 of the arms 29, 30 into the slots 22, 23, as shown clearly in Fig. 2, each hump being disposed between the perforated lugs 19 of 85 the eye shell structures. This disposes the bottoms of the gaps or openings within the humps 32, 33 in line with the perforations in the lugs 19. The bridge rod 17 is then passed through the said perforations and the gaps 90 in the humps 32, 33 so that the parts are assembled and may be adjusted to the position substantially as shown. Thereby the eyes are securely united and they are firmly attached to the arms 29, 30 from which the weight 24 is suspended, and the binding relation established between the hump portions of the arms, the bridge rod 17, and the eyes acts to hold the eyes firmly upon the humped portions of the arms. Consequently, the eyes 100

will always move in consonance with the oscillating movement of the weight 24, and the eyes will be held in proper registration with the eye sockets in the face portion 10, whereby the proper rolling motion of the eyes will be obtained. The described eye mechanism is but one example of many constructions which may be used with the present invention.

Usually the eyes are supported from the head of the doll or the like in a more or less makeshift and unmechanical manner, and they sometimes become loose or detached from the head. An important object of this invention is to provide reliable means for firmly anchoring the eye set at its point of attachment to the head. To this end, an anchor member 34 is provided in the form of a disk composed of suitable, stiff, fibrous material, or any other suitable material may be employed which is preferably slightly yielding or resilient. Anchor member 34 is provided with a more or less centrally disposed supporting loop or stud 35, which is provided with outwardly and rearwardly bent ends 36, all as more clearly shown in Figs. 1, 2 and 3. The supporting loop with its bent ends 36 is preferably composed of a single strip of sheet metal bent in the proper shape. The loop or stud 35 extends through a preferably enlarged central opening in the anchor member 34 and the bent ends thereof are extended outwardly along the forward face of fibrous member 34 and then rearwardly through the material of said member. Thereby the anchor member and the supporting loop or post 35 are securely connected together. The anchor member 34 is secured to the forehead portion of the head of the doll in any suitable manner. Preferably, this is accomplished by means of a suitable filling 37 of glue or cement between the anchor member 34 and the forehead of the doll, the glue extending around the edges of said member, which is strongly bound with the glue on account of its fibrous nature. Preferably, the back of the doll's forehead is provided with an inwardly raised seat portion 38 formed up from the material of the doll's head and having a depression 39 slightly larger than the anchor member 34, so that the latter may be pressed onto the glue in said depression and firmly seated in proper position.

Suitable means are provided for attaching the doll eye set to the anchor member 34 and the support or post 35. The attachment is preferably such as to render the set removable. To that end, the doll eye set is provided with a hanger bracket 40 formed from a plate of sheet metal having bent therefrom parallel side flanges 41. The edges 42 of the flanges are preferably serrated or suitably formed with penetrating points. The hanger bracket 40 is furthermore provided with flanges or ears 43 at the lower end thereof, and these are formed with slots 44 which ex-

tend transversely to the back of the hanger bracket. Spring legs 45 are provided which are preferably formed from a single piece of spring steel wire bent into bifurcated form. The connecting portion between the spring legs is inserted into a slit 46 cut in the metal hanger bracket 40; and the latter is clenched upon the said connecting portion so as to firmly secure the spring legs in such position that they will extend downwardly between the flanges or ears 43. The free ends of these spring legs 45 bear in a forward direction upon the bridge rod 17 on which the eyes 11, 12 are mounted, thereby forcing the eyes forwardly to their bearing relation with the surfaces of the eye sockets.

In order to properly assemble and combine the doll eye set rigidly with the head of the doll, the hanger bracket 40 is provided with an aperture 40^a so that the parts may be engaged, the supporting loop or stud 35 passing through the aperture 40^a and extending rearwardly of the hanger bracket 40. A metallic wedge 46^a, preferably formed similarly to a cotter pin, is now driven through the rearwardly projecting portion of the supporting loop 35, its straight face bearing upon the adjacent surface of the hanger bracket. When the wedge 46^a is driven in as far as required, the doll eye set and the hanger bracket will be firmly bound together, and the serrations 42 will be caused to penetrate more or less the preferably non-metallic anchor member 34. By this preferred construction, not only is the hanger bracket 40 precluded from longitudinal movement but from lateral movement, whereby the eyes 11, 12 are held in position for fitting into the eye sockets.

It is apparent herefrom that the bracket plate 40 is freely movable about the stud 35, before the insertion of the wedge 46^a, in order to provide for its angular adjustment, and hence the movement of the eyes 11, 12 into their sockets, and when the desired relations have been obtained the adjustment is held as set, upon the insertion of the locking wedge. When the wedge is forced tight the cement filling 37 holds the fiber anchor member 34 and there is no tendency by the wedge to pull or loosen the anchor member from its anchorage with the forehead portion of the doll. The assembly of the bracket plate 40 on the stud 35, the adjustment of the bracket plate to proper position, and the insertion of the wedge 46^a can obviously be easily accomplished through the neck opening of the doll head. Also, the slight resiliency of the back portion of the bracket 40 being sufficient to enable the wedge 46^a, which bears thereon, to be forced tightly into the loop or stud 35, the anchor member 34 being slightly resilient or yielding, and the serrations of the flanges 41 of the bracket plate sinking into the yielding material of the anchor member,

it will be understood that the several resilient features mentioned act to hold the wedge 46^a efficiently notwithstanding that there may be shrinkage or expansion of the parts. The 5 serrations of the bracket flanges 41 by biting into the anchor member 34 permanently retain the bracket plate against any movement relative to the anchor member at all times. Another advantage gained by the preferred 10 construction is that the upper end of the spring steel wire 45, together with its retaining means, provides a suitable roughened surface which is engaged by the wedge 46^a and is thereby held against accidental displacement, because the wedge is preferably of 15 softer metal than the spring steel wire.

In the modification shown in Fig. 5, the bracket 47 is of the preferred construction and likewise the anchor member 48. However, in this form of the invention, a screw-threaded headed stud 49 is passed through the anchor member 48 so that its head will bear upon the front surface of the anchor member 48, the screw-threaded portion of 25 the pin protruding through the hanger bracket 47. Onto the screw-threaded end of the stud 49 there is then engaged a nut 50, which, when it is screwed home, will firmly secure the parts together. In both of the illustrated 30 forms of the invention, however, the doll eye set may be detached from the head of the doll or the like whenever it is desired to adjust or reconstruct portions thereof.

It is obvious that the invention is susceptible of modification, as parts may be omitted, 35 added, and substituted, and still be within the spirit of the invention without departing from the scope of the appended claims.

What I claim as new is:

1. In a doll eye set, the combination of anchoring means composed of yielding material and for attachment to a head, a hanger-bracket having serrated edges, and for supporting a pair of eyes, and securing means for pressing the serrated edges into said anchoring means.

2. In a doll eye set, the combination of an anchoring member, a supporting loop extending from and firmly secured to the anchor 50 member, a hanger-bracket for supporting the eyes and having an opening through which said loop extends, and a wedge driven between the outer end of the loop and the adjacent part of the hanger-bracket for removably securing the same to the anchor member.

3. In a doll eye set, the combination of anchoring means composed of yielding material and for attachment to a head, a hanger-bracket provided with side flanges having serrated 60 edges, and for supporting eyes, securing means for pressing the serrated edges into said anchoring means, and eyes supported by said hanger bracket.

4. In a doll eye set, the combination of an 65 anchor member, a supporting loop extending

from and firmly secured to the anchor member, a hanger-bracket for supporting eyes and having an opening through which said loop extends, the back of said bracket being resilient, and a wedge driven between the outer end of the loop and the resilient back of the hanger-bracket for removably securing the same to the anchor member.

5. In a device of the class described, the combination with a doll head or the like made of relatively non-yielding material, of an anchoring member composed of a relatively more yielding material, means to fix said anchoring member within the head, a hanger bracket engaging said anchoring member, 70 eyes carried by said bracket, and securing means arranged to press portions of the bracket into the yielding surface of said anchoring member to thereby support the bracket.

6. In a device of the class described, the combination with a doll head or the like, of anchoring means arranged within said head composed of yielding material and having an opening therethrough, a stud having a head portion engaging one surface of said anchoring means and having another portion projecting through said opening, said stud having an opening formed through itself, an eye set comprising a bracket member telescoping over the projecting portion of said stud and engaging said anchoring means, a wedge member engaging between the projecting portion of said stud and said bracket member said wedge being inserted through the opening in said stud and exerting a tensional strain upon the stud and a compression strain against the bracket member to thereby clamp the bracket member against the yielding material comprising the anchoring means, and eyes supported by said bracket 85 member.

7. In a device of the class described, the combination with a doll head or the like, of anchoring means arranged within said head composed of yielding material and having an opening therethrough, a stud having a head portion engaging one surface of said anchoring means and having another portion projecting through said opening, an eye set comprising a bracket member telescoping over 90 the projecting portion of said stud and engaging said anchoring means, the stud having a surface arranged in opposition to the bracket member, a wedge member engaging between the mentioned surface of said 95 stud and said bracket member exerting a tensional strain upon the stud and a compression strain against the bracket member to thereby clamp the bracket member against the yielding material comprising the anchoring means, eyes supported by said bracket member.

8. In a device of the class described, the combination with a doll head or the like, of anchoring means arranged within said head composed of yielding material and having an opening therethrough, a stud having a head portion engaging one surface of said anchoring means and having another portion projecting through said opening, an eye set comprising a bracket member telescoping over 110 the projecting portion of said stud and engaging said anchoring means, the stud having a surface arranged in opposition to the bracket member, a wedge member engaging between the mentioned surface of said 115 stud and said bracket member exerting a tensional strain upon the stud and a compression strain against the bracket member to thereby clamp the bracket member against the yielding material comprising the anchoring means, eyes supported by said bracket member movable with respect thereto, spring means engaging between the eyes and the bracket member to urge the eyes in one direction with respect to the bracket member, and 120

said spring means having a part arranged to engage said wedge for retaining the wedge against displacement.

8. In a doll eye set, the combination of anchoring means for attachment to a head, a hanger bracket for supporting a pair of eyes, the anchoring means and the hanger bracket having parts providing opposingly facing surfaces, and a separate wedge to engage said opposingly facing surfaces for securing the hanger bracket to the anchoring means.

9. In a doll eye set, the combination of anchoring means for attachment to a head, a hanger bracket for supporting eyes, said hanger bracket having a front portion engaging the anchoring means and having a resilient flexible back portion, and means engaging between said anchoring means and said resilient back portion of a character to flex the back portion and thus resiliently force the front portion of the bracket into firm engagement with the anchoring means.

10. In a doll eye set, the combination of yielding anchoring means for attachment to a head, a hanger bracket for supporting eyes, said hanger bracket having a front portion engaging the anchoring means and having a resilient flexible back portion, and a detachable wedge mutually engaging said resilient back portion and said anchoring means for detachably securing the hanger bracket to the anchoring means and causing slight embedding of the hanger bracket into the anchoring means.

35 11. The combination with a doll head, of an eye set therefor comprising a pair of eyes, a bridge rod extending between and supporting said eyes, and attaching means for the bridge rod comprising a loop connected with the doll head, a bracket member connected with the bridge rod having telescoping relation with said loop, and a wedge extending through the loop in frictional engagement therewith and with the bracket member.
